GUIDE DEVICE

Filed Nov. 24, 1936

UNITED STATES PATENT OFFICE

2,141,130

GUIDE DEVICE

Stevenson Findlater, McKeesport, Pa., assignor to
National Tube Company, a corporation of New
Jersey

Application November 24, 1936, Serial No. 112,588

3 Claims. (Cl. 80—13)

This invention relates to rolling mills, and more particularly to guide devices therefor.

In my co-pending application, Serial No. 100,535 filed September 12, 1936, there is disclosed a guide device for rolling mills and particularly those which roll seamless tubes. The device of the present application is generally similar thereto but includes additional elements which make for greater efficiency.

10 It is among the objects of the present invention to effectively sectionalize rolling mill guide devices and provide for their efficient support as a unitary structure; the sections being relatively small to eliminate the discard or interchange of more than is necessary.

15 The foregoing and other objects will be apparent after referring to the drawing, in which:

The single figure is a sectional elevation of the device of the invention as applied to a conventional type of seamless tube mill.

20 Referring more particularly to the drawing, the numerals 1 and 2 respectively designate the usual upper and lower chairs for the guide devices which are customarily employed intermediate the metal-working rolls of the mill.

25 According to the teaching of the invention, the upper chair 1 carries a pair of horizontally extending pins 3 and 4 which are substantially spaced with respect to each other. The pin 3, which is most adjacent the inlet end of the mill, carries a movable bellcrank lever 5, one end of which extends rearwardly and horizontally, as shown at 6. One end of a vertically extending shaft 7 is pivotally connected, as at 8, to the end 26 of the bellcrank lever 5. The other end of the shaft 7 is extended through an ear 9 which is integrally formed on the upper chair 1. This end of the shaft 7 is screw-threaded to carry an adjusting nut 10 in contact with the ear 9, whereby the bellcrank lever 5 may be partially rotated on the pin 3. The other end of the bellcrank lever 5 extends downwardly, as shown at 12, and carries a rearwardly extending lug 13, whose rearward face 14 is mitered.

30 The forward part of the upper guide element per se of the invention is shown at 15 as comprising a metallic segment which has forward and rearward mitered projections 16 and 17, respectively. This segment 15 is provided with a recess 18 whose forward wall is mitered, as shown at 19. An insert 20 is disposed in the recess 18 and has a forward mitered projection 21 for contact with the mitered wall 19 of the recess 18. Between the lower side of the recessed portion 18 of

the segment 15 and the upper side of the insert 20 there is disposed a liner 21a.

35 The forward mitered projection 16 of the segment 15 is engaged by the mitered face 14 on the bellcrank lever 5. The insert 20 also has a rearward mitered projection 22 for a purpose to be later described.

40 The rearward pin 4 on the upper chair 1 carries a bellcrank lever 25, one end of which extends rearwardly and horizontally, as shown at 26. One end of a vertically extending shaft 27 is pivotally connected, as at 28, to the end 26 of the bellcrank lever 25. The other end of the vertical shaft 27 is extended through an ear 29 which is integrally formed on the upper chair 15. This end of the shaft 27 is screw-threaded to carry an adjusting nut 30 in contact with the ear 29, whereby the bellcrank lever 25 may be partially rotated on the pin 4. The other end of the bellcrank lever 25 extends downwardly, as shown at 32, and carries a rearwardly extending lug 33 whose rearward face 34 is mitered.

45 The rearward part of the upper guide element per se of the invention is shown at 35 as comprising a metallic segment which has upper and lower forward mitered projections 36 and 37 respectively. The upper forward mitered projection 36 is engaged by the mitered surface 34 on the rearwardly extending lug 33 on the bellcrank lever 25. The lower forward mitered projection 37 engages the rearward mitered projection 22 of the insert 20 in the segment 15.

50 The segment 35 of the upper guide element per se also carries a rearwardly extending mitered projection 38 which makes contact with a forward mitered projection 40 on the upper chair 1.

55 Liners 43 are disposed between the upper chair 1 and the upper surfaces of the segments 15 and 35 to adjust the latter with respect to the horizontal center-line of the pass. This enables compensation for wear.

60 The lower chair of the mill is arranged in sections, as shown at 2 and 2a, the former being mounted on a conventional vertical adjusting device. The forward section 2 of the lower chair carries a pair of horizontally extending pins 53 and 54 which are substantially spaced with respect to each other. The pin 53, which is most adjacent the inlet end of the mill, carries an intermediate pivoted vertically extending lever 55. The vertically extended end 56 of the lever 55 carries a rearward horizontally extending lug 57, the rearward face of which is mitered, as shown at 58. The downwardly extending end 59 of

of the vertical lever 55 carries a pin 60 to which there is connected the one end of a forwardly extending rod 61. The other end of the forwardly extending rod 61 extends out of the forward section 2 of the lower chair and carries an enlarged washer 62 and an adjusting nut 63. The adjusting nut 63 engages the enlarged washer 62 and enables the movement of the forwardly extending rod 61.

1 The forward part of the lower guide element per se is shown at 65 as comprising a metallic segment which has forward and rearward mitered projections 66 and 67 respectively. This segment 65 is provided with a recess 68 whose forward wall is mitered, as shown at 69. An insert 70 is disposed in the recess 68 and has a forward mitered projection 71 for contact with the mitered wall 69 of the recess 68. Between the upper side of the recessed portion 68 of the segment 65 and the lower side of the insert 70 there is disposed a liner 71a. The forward mitered projection 66 of the segment 65 is engaged by the mitered face 58 on the vertical lever 55. The insert 70 also has a rearward mitered projection 72 for a purpose to be later described.

2 The rearward pin 54 on the forward section 2 of the lower chair carries a vertically extending lever 75 whose upper end 76 has a rearwardly extending lug 77. The rearward face of this lug 77 is mitered, as shown at 78. A pin 80 is carried on the intermediate portion of the vertical lever 75 for supporting one end of a rearwardly extending rod 81, the other of which extends through and out of the rearward section 2a of the lower chair.

3 The rearward part of the lower guide element is shown as comprising a metallic segment 85 which has upper and lower forward mitered projections, 86 and 87, respectively. The upper forward mitered projection 86 engages the rearward mitered projection 72 on the insert 70, while the lower forward mitered projection 87 makes contact with the mitered face 78 on the vertically extending lever 75. This segment 85 also carries a rearwardly extending mitered projection 88 which makes contact with a forward mitered projection 89 on the forward section 2 of the lower chair.

4 Immediately below the position where the extended end of the rod 81 emerges from the rearward section 2a of the lower chair there is disposed an ear 91 on which there is mounted a pin 92. A vertically extending clamp 93 is connected to this pin 92. The upper end of the clamp 93 carries a forwardly extending lug 95 whose forward face is mitered, as shown at 96. The end of the rod 81 which extends through the clamp 93 carries an adjusting nut 100.

5 The upper surface of the rearward section 2a of the lower chair carries a secondary guide element 102 in the form of a plug trough. This secondary guide element 102 has an intermediate downwardly extending portion 104 which carries a forwardly extending mitered projection 105. This mitered projection 105 makes contact with a rearwardly mitered projection 106 on the section 2a of the lower chair.

6 The guide element 102 also carries a downwardly and rearwardly extending lug 107 whose rearward face 108 is mitered for contact with the mitered face 96 of the lug 95 on the clamp 93.

7 Liners 114, 113 and 112 are disposed between the sections 2 and 2a of the lower chair, and the lower surfaces of the respective elements 65, 85 and 102, to adjust them with respect to the horizontal center line of the pass.

8 It is to be noted that the segments 15 and 65, inserts 20 and 70 and segments 35 and 85 are identical and therefore interchangeable, whereby complexity is avoided.

9 While I have shown and described one specific embodiment of my invention, it will be understood that I do not wish to be limited exactly thereto, since various modifications may be made without departing from the scope of my invention, as defined by the following claims.

10 I claim :

11 1. The combination with an axial tube rolling mill of upper and lower oppositely disposed work-piece guide devices disposed intermediate the metal work rolls, comprising a pair of oppositely disposed supports, a stationary guide element in each of said supports, means for holding said guide elements in contact with their respective supports, a second stationary guide element in each of said supports, means for moving said second named guide elements towards the said first named guide elements and an insert carried by each of the said second named guide elements, said inserts being constructed and arranged to be rigidly held in position within their respective guide elements and against said first named guide elements by moving said second named guide elements toward the said first named guide elements.

12 2. The combination with an axial tube rolling mill of upper and lower oppositely disposed work-piece guide devices disposed intermediate the metal-working rolls comprising a pair of oppositely disposed supports, means for holding said guide elements in contact with their respective supports, a second stationary guide element in each of said supports, means for moving said second named guide elements towards the said first named guide elements, and an insert carried by each of the said second named guide elements, said inserts being constructed and arranged to be rigidly held in position within their respective guide elements and against the said first named guide elements by moving said named guide elements toward the said first named guide elements, the contacting surfaces of said inserts and said first and second named guide elements being mitered.

13 3. The combination with an axial tube rolling mill of a stationary work-piece guide device disposed intermediate the metal-working rolls comprising a support, a stationary guide element, means for holding said guide element in contact with said support, a second stationary guide element, means for moving said second-named guide element towards said first named guide element, and an insert carried by said second-named guide element, said insert being constructed and arranged to be rigidly held in position on said second named guide element and against said first named guide element by moving said second named guide element toward the first named guide element, the contacting surfaces of said insert and said first and second named guide elements being mitered.

14 STEVENSON FINDLATER.
